(57) **CLAIM**

The ornamental design for a cymbal with surface holes, as shown and described.

DESCRIPTION

FIG. 1 is a top perspective view of a cymbal with surface holes showing our new design;

FIG. 2 is a top elevation view thereof;

FIG. 3 is a bottom elevation view thereof;

FIG. 4 is a right side view thereof;

FIG. 5 is left side view thereof;

FIG. 6 is a front view thereof; and,

FIG. 7 is a rear view thereof.

(Continued)

The broken lines in FIGS. 1-7 represent the portions of the cymbal with surface holes which form no part of the claimed design.
